FILE SYSTEM

Application filed November 2, 1923. Serial No. 672,322.

My invention relates to card index systems and more particularly to a directory or index guide for a list of names.

The present index consists of a collection 5 of sheets, each containing a list or plurality of names. The collection of name lists are divided into groups alphabetically, so that the lists in each alphabetical group contain only family names beginning with the same 10 letter. These family name groups are separated by correspondingly initialed guides. Each group of data sheets or lists of family names having like first letters are further sub-divided according to the second letter of 15 the family name, and these subdivisions may be further divided according to the third letter of the family name. Such classification may be extended to include any number of identification letters.

20 Whether the provision of the lists of names is carried through the second, third and subsequent letters of the family name, or whether such sheets and lists are divided only in accordance with the first letters of 25 the family names, and regardless of the subsequent letter, the given name or initial of the given name of the individuals are spaced across the sheet in alphabetical relation. The given names or initials of given names 30 are thus arranged in different rows upon the sheet whereby all the first names or initials beginning with "A" are found in the first column, those beginning with "B" are found in the second column, those having "E" for 35 the first letter being found in the fifth column, and so forth. Inasmuch as among a considerable group or number of persons having similar family names or names of which the first one, two or three letters may 40 be identical, there will be very few such persons who possess identical given or first names, or first names having identical initials. Consequently the distribution of the given names or first name initials across the 45 sheet in different columns of alphabetical succession affords a further division or separation of such individuals into groups or classes of small numbers, which facilitates the selection of a particular name. 50 The sheets or lists of names may have asso-

ciated therewith, the addresses of the individuals, numbers indicative of ledger accounts, contracts, insurance policies or the like, or there may be associated therewith symbols indicative of the individuals financial or credit rating, or figures indicative of his credit limit, amount due, or other general information.

The object of the invention is to simplify such index or directory systems, whereby 55 they will not only be inexpensive, but will be more efficient in operation, compact, but permitting a vast number of names and data pertaining thereto to be arranged in minimum space, readily accessible to enable the 60 selection of a desired name with minimum movement and with great rapidity or speed of operation.

A further object of the invention is to provide a system wherein entries may be 65 made upon the card, either by hand writing or by passing the cards through a typewriter, or calculating machine, by which names and numbers or amounts may be entered, directly 70 thereon.

A further object of the invention is to provide a system, whereby particular or individual names may be readily and quickly found, even though the names are not arranged in regular order or sequence upon a 75 particular data or list sheet.

A particular feature of the invention is the classification of the names by the first name initials, thereby facilitating the ease and speed of selection.

With the above primary and other incidental objects in view as will more fully appear in the specification, the invention consists of the features of construction, the parts and combinations thereof, and the arrangement of the cards, and the distribution of names and initials thereon, and the mode of operation or their equivalents as hereinafter described and set forth in the claims.

In the accompanying drawings, wherein is 95 shown the preferred, but obviously, not necessarily the only form of embodiment of the invention, Fig. 1, is a front elevation of a collection of data sheets or name lists, illustrating the embodiment of the invention. 100

Fig. 2 is a similar view of the top or side portion only of the groups of sheets, or leaves, pertaining to one family name initial. Fig. 3 is a somewhat diagrammatic view illustrating the data sheets or lists pertaining to the sub-division and the method of locating selected names upon the different data sheets or leaves.

Like parts are indicated by similar characters of reference throughout the several views.

In the drawings, 1 indicates a collection of data sheets or leaves, each bearing a list of names of greater or less extent. These leaves or data sheets may be of any suitable size, either as to width or to height, necessary to accommodate the desired number of names, and accompanying data or information. Inasmuch as these sheets are oscillated to and fro or separated into portions to expose a desired data sheet or leaf in the manner of the ordinary and usual index file system, they are preferably mounted in a suitable holder or carrier. Such holder or carrier may be similar to a ring book, a loose leaf binder or a card file box. The particular form of holder or mounting forms no part of the present invention.

The data sheets or leaves 1 are divided into groups alphabetically designated in accordance with the first letters of the family names, entered upon the different sheets. In Fig. 1, four of these primary alphabetical groups have been shown. The groups are identified by the family name initials, "H", "I", "J" and "K", located upon guide tabs indented from the left at the top of the data sheets or cards as shown at 2. All of the data sheets in each of these groups bear a list of names having corresponding initials for the family names. That is to say, all the names appearing upon the data sheet in the group "J" have family names beginning with J, while those in the group "H" bear names of which the family name begins with H.

The data sheets or leaves of each of these primary groups are sub-divided alphabetically in accordance with the second letter of the family name. This second grouping or sub-division will not involve all the letters of the alphabet. By referring to city directories, telephone directories and other large lists of names, it will be found that the first two letters of the names appear in certain rather limited combinations, but which differs somewhat for names having different initial letters. It so happens that the names beginning with H almost invariably employ a vowel, "a", "e", "i", "o" or "u" as their second letter. (As is shown in Fig. 1.) However, the present system is not founded upon the vowel sequence. To illustrate the variation naturally occurring in various directories and lists of names, the second letter sub-divisions of the primary "C" group have

been illustrated in Fig. 2. It is found that an initial C is usually found followed by "a", "e", "h", "i", "l", "o", "r" or "u". Such subdivision guide designations appear at 3 upon the intermediate data sheets or leaves between the primary guide designations 2, and are also indented from the left to a greater extent than the primary designations 2. However, ordinarily these sub-division designations or intermediate group guides 3 are concealed between the primary guides 2, and are not visible until the collection of leaves or sheets is separated in accordance with the primary guides 2.

The data sheets or leaves 1 comprising the secondary group or sub-divisions indicated by the guide letters 3, are further separated according to the third letter of the family name. However, to economize space, and make the index compact, and in view of the fact that lists of family names having the first three letters identical will not be very extensive, it will be found desirable to place upon the same data sheet or leaf, names of which the first two letters may be identical, but the third letter may differ. For instance in Fig. 1, there are shown upon the same leaf or sheet, names beginning Hea, Hec, Hed, Hee, Hef, and Heg. It is not necessary for the purpose of this index, nor to facilitate the finding of particular names, that the names be arranged in alphabetical succession, as to such third letter. For example in Fig. 1, the same family names are found at both the top and bottom of the list, while near the middle of the list a name having Heg. precedes Heb. Each data sheet or leaf carries upon its guide tab at the top of a sheet, a third series of index letters 6, pertaining to the third letter of the family name. The guide tabs carrying such third position index letters are indented from the right, in overlapping relation, or echelon, to expose to view upon each leaf or sheet the particular letters, comprising the third position letters of the family names, appearing upon that particular sheet. In the particular data sheet illustrated in Fig. 1, there will be carried the family names beginning Hea to and including Heh. Consequently, the index tab for the third position letters 6, displays the first eight letters of the alphabet. Upon the next sheet of the secondary group 3, shown in Fig. 1, or that sheet immediately behind the one exposed to view will be found the names beginning Hei, Hej, Hek and Hel. These particular index letters are displayed upon the guide tab portion projecting beyond the foremost sheet. The next or third sheet will contain the family names beginning Hem, to and including Heq, which guide letters are displayed upon the exposed portion of the overlapping tab. The apportionment of the third position letters to the different sheets will depend somewhat upon the extent of the

list of names and the similarity. This allotment or arrangement of the third position letter guide is not arbitrarily fixed. This can only be determined at the time the names are written or printed upon the respective sheets. If there are so many names beginning Hea and Heb as to fill the entire sheet or approximately fill the same, all those names beginning Hec, Hed, etc. will be placed on the succeeding sheet or leaf until that also is filled. If there are more names in any such third position classification than can be contained upon any one data sheet or leaf, additional leaves may be inserted in front of the third letter index sheet, and the heading or index letters omitted from such inserted or supplemental sheet or leaf. For convenience the data sheets or leaves are preferably, though not necessarily originally printed with the complete alphabet extending across the sheet or leaf adjacent to its top margin. As the list of names are entered upon the several sheets, the top margins are cut away or indented from the right to whatever extent may be necessary, in order that there may be left exposed to view those letters only, which comprise the third position letters, of family names appearing upon that particular sheet. When the sheets are assembled, the overlapping exposed portions of the tabs or lettered top portions display the full alphabet in regular succession.

Each of the data sheets or leaves bears a list of family names 4, having as their initial letter, the designating letter of the primary group 2 and as the second letter of such family name, one corresponding to the identifying letter 3 of the secondary group or subdivision. In the present instance, the column of family names has been shown arranged at the left of the sheet. In addition to the column 4 of family names, each sheet is divided into a series of columns 5, corresponding to the different letters of the alphabet. The initials of the first or given names of the individuals, whose family names appear in the column 4 are written upon the sheet with the first name initial located in the corresponding alphabetical column 5. For instance, the initial C of the name Charles appears in the third column or C column, while the initial H of the name Howard appears in the H column, being offset toward the right beyond the name Charles, as also the name Harry. The initials V L are located with the V in the corresponding alphabetical column, while William is located one column further to the right. This affords a very definite classification, in which few of the names will fall into each class and in which these few may be readily distinguished from the others. It will be noted that on the fragment of data sheet shown in Fig. 1, there are twenty-seven family names, of which only three have given names begin-

ning with A, one with B, two with C, and one each in the J, L, N, P, S, T and W classes or columns. Having found the sheet containing the desired family name by the guide letters 2 and 3, it is not necessary to search in the column 4, the particular name, but by glancing down the column 5 pertaining to the initial of the first or given name, the desired name is readily found.

The lettered tabs or top margins of the sheet serve the double purpose of the family name third letter index, and also as an index or guide letter for each of the alphabetical columns pertaining to the first or given names. While the letters pertaining to certain initial or first name column 5 may have been cut off of the data sheet, such columns will align with the correspondingly lettered columns of the next succeeding sheet. Since as before mentioned, the overlapping exposed portion of the lettered margins of the sheet display the complete alphabet, the initial or first name columns 5, are readily selected.

In Fig. 3, the sheet pertaining to the secondary group or sub-division R of the primary group or division B have been shown separated from each other, and by means of lead lines the manner of employing the index for the location of particular names has been illustrated diagrammatically. Assuming that the desired name is that of Charles Brady, the collection of leaves or data sheets is separated according to the primary guide letter B. By separating the collection of leaves at this point, the secondary guides 3 are then exposed, and such secondary group is separated at the index letter R. This exposes to view the overlapping letter tabs or top margins of the several sheets, arranged in echelon, to display the complete alphabet. While the letters A, B, C and D appear on each of the leaves 1A, 1B, 1C and 1D, it is only the first leaf 1A which is in view when the index is open, at the guide R. All of the names beginning Bra, Brb, Brc and Brd are upon this first sheet. It is not necessary to look down the column of family names to find the name Brady, which may be located, either near the top or the bottom of the column, but since the desired name is Charles Brady, the searcher glances down the C column. While there may be several initials C appearing in this column, there is likely to be only one Charles Brady, although there may be numerous other Bradys. If the desired name is that of John Brock, the initial letter B is found in the primary index 2, and the separation of this sheet will expose to view the letter guides 3 of the secondary group or sub-division in which the R is selected, and upon opening the collection of sheets at the point indicated by the R, there is exposed to view the complete alphabet distributed upon several indented sheets, 1A, 1B, 1C, 1D and

- 1E. These sheets are separated to expose the sheet upon which the third letter O appears. Without looking down the family name column to find the name Brock, the observer looks down column J to find John. Inasmuch as there will be comparatively few names where the first name is John, the search is thus limited to a very few family names.
- 10 To find the name William Brinkle, the same procedure is employed. The first letter B is found in the primary guide index 2, and the collection of sheets of the index is accordingly separated. This exposes the secondary index 3, and the second letter of the name Brinkle, to wit: r is selected. Upon opening the series of leaves in accordance with the guide letter r, there is exposed to view the complete alphabet appearing upon 20 the overlapping portions of the top margins or tabs of the several sheets 1A to 1E inclusive. The sheet upon which the letters i are exposed is then selected, but without referring to the family name column 4 upon such sheet, the observer looks down the column 5, which registers with the letter W, and finding the initial W or name William, glances across to the column 4 until he finds such name William or initial W, alined with the family name Brinkle. Thus instead of searching through the entire column 4 for the particular family name, of which duplicates may numerously occur, the field of search is restricted to very narrow limits by searching 30 for the first or given name, and then fitting such given name to the family name.
- 35 The system described enables a desired name to be very quickly located, and permits a large number of names to be arranged in a small compact file unit. In actual practice, a name index system such as described, having a capacity of seventeen thousand names and actually containing more than twelve thousand names has been embodied in a collection of data sheets or leaves having a thickness of approximately three fourths of an inch.
- 45 While as before mentioned the third letter index 6 at the top margin of the sheet serves also as the index for the columns 5, pertaining to the first name initials, if desired a second series of index letters 7 may be provided for the columns 5, although such additional columnar index 7 is not essential nor necessary.
- 50 A particularly advantageous feature of the present system is that additional names may be added at the end of the list without regard to the sequence of letters, and such names 55 may be equally as easily selected or located as if placed in regular order or sequence. For instance, in the ordinary directory or index arrangement, names beginning Heb necessarily follow the Hea names, and Hec follow Heb etc. Most index files are depend-

ent upon some mechanical feature which enables additional names to be inserted in proper sequence and such sequence is ordinarily essential to the rapid and accurate selection of names. Referring to Fig. 1, it is to be noted that the last two family names on the list shown are the same as the first two names, and at the middle of the lists the name Heddle precedes the name Hecht, and also at the bottom of the list, the name Hebelman is preceded by the name Hegman. Nevertheless these names are selected or located with equal facility by the first name selective system, herein described and it is not at all necessary that they should be arranged in any particular order upon the data sheet or list.

In files wherein the names are arranged in sequence, the insertion of other names necessitates a shifting of the original names and a variation of spacing or location. In the present device the locations of names are not changed and the operator is enabled by habit to quickly locate a name in its accustomed place.

The data sheets all contain names and initials, and no blank sheets or subdivision sheets are necessary as is usual with most of the alphabetical filing systems, to accommodate new names. However, blank lines are left on each sheet for this purpose and when these lines are all filled, a supplemental sheet is inserted.

From the above description it will be apparent that there is thus provided a device of the character described possessing the particular features of advantage before enumerated as desirable, but which obviously is susceptible of modification in its form, proportions, detail construction and arrangement of parts without departing from the principle involved or sacrificing any of its advantages.

While in order to comply with the statute the invention has been described in language more or less specific as to structural features, it is to be understood that the invention is not limited to the specific details shown, but that the means and construction herein disclosed comprises the preferred form of several modes of putting the invention into effect and the invention, is therefore, claimed in any of its forms or modifications within the legitimate and valid scope of the appended claims.

Having thus described my invention, I claim:

1. A series of sheets, an appropriate column located in the same position on each of the sheets for the entry therein of lists of family names, each sheet bearing a transversely disposed succession of letters of the alphabet, letters carried by succeeding sheets being simultaneously exposed to present to view a substantially complete alphabet, a series of columns appropriately designated by the alphabetical succession of letters for

- the entry of given name initials pertaining to the family names on a sheet and corresponding to such alphabetical column designations, like positions upon the succeeding 5 sheets being occupied by columns pertaining to like initials.
2. A series of sheets, a column on each sheet appropriate for the entry of lists of family names, and a series of vertical columns on 10 each sheet for the entry of corresponding individual name initials opposite the family names, each sheet bearing a transversely disposed succession of the letters of the alphabet consecutively arranged, the sheets being 15 arranged in overlapping relation to expose to view upon each sheet a different group of successive letters of the alphabet, which designate said vertical columns upon the several sheets in which to locate given name 20 initials of names entered upon such sheets.
3. A series of sheets, a column of spaces on each sheet appropriated to the entry of lists of family names, and a series of additional columns of spaces on each sheet for the 25 entry of corresponding individual name initials opposite the family names, each sheet bearing a transversely disposed succession of the letters of the alphabet consecutively arranged in the said additional columns, the 30 sheets being arranged in overlapping relation to expose to view upon each sheet a different group of successive letters of the alphabet, which exposed letters comprise guide symbols corresponding with a predetermined ordinate of the letters of the family 35 names entered upon such sheet and simultaneously designating the transverse position of particular spaces of the said additional series to receive corresponding given name 40 initials pertaining to such family names.
4. In a name index, a series of overlapping sheets, suitable spaces thereon appropriated to the entry of a series of family names, and additional appropriately designated spaces 45 for the entry of individual name initials, the exposed portions of the sheets bearing different letters presenting to view in combination substantially a complete alphabet, the letters of which comprise duo-functional 50 guides corresponding to predetermined ordinal letters of the family names appearing upon the same sheets and designating the transverse positions upon the sheets of said spaces for the entry of given name initials 55 pertaining to the family names.

In testimony whereof, I have hereunto set my hand this 30th day of October, A. D. 1923.

RODNEY J. WOOD.
